Primary Examiner — George D. Kirschbaum*Assistant Examiner* — Lillian Windham(74) *Attorney, Agent, or Firm* — William J. Clemens; Shumaker, Loop & Kendrick, LLP(57) **CLAIM**

The ornamental design for an elevator car operating panel, as shown and described.

DESCRIPTION

FIG. 1 is a front view of an elevator car operating panel showing our new design; and,

FIG. 2 is a front view of a second embodiment thereof. The broken lines in the figures show portions of the elevator car operating panel that form no part of the claimed design.
